UNITED STATES PATENT OFFICE.

ALEXANDER L. HOLLEY, OF BROOKLYN, NEW YORK.

BESSEMER CONVERTER.

SPECIFICATION forming part of Letters Patent No. 240,714, dated April 26, 1881.

Application filed June 17, 1880. (No model.)

To all whom it may concern:

Be it known that I, ALEXANDER LYMAN HOLLEY, of the city of Brooklyn, county of Kings, and State of New York, temporarily residing at the Hotel de France et de Bath, in the city of Paris, in the Republic of France, have invented a certain new and useful Improvement in Bessemer Converters, of which the following is a specification.

10 The ordinary vessel or converter for refining crude iron by the Bessemer process consists of an iron shell, which contains the refractory lining and a "bottom," which contains the tuyeres and tuyere-box. To the shell two 15 trunnions are permanently secured, by means of which the converter is supported, rotated, and supplied with blast. As the tuyeres are rapidly destroyed during the refining operation the bottom is usually made removable, 20 so that a repaired bottom can be quickly substituted. The lining of the shell is more durable; but when it is made of lime or other materials which require frequent repairs it is necessary to change the lining as well as the 25 bottom with celerity, so that the operations of refining may go on without delay. For this purpose the entire converter, with its trunnions, may be lifted out of its seat and carried away for repairs by means of a traveling crane, 30 and a repaired converter may be substituted; but the apparatus for this purpose is costly, and much time and labor are necessary in removing pillow-block caps and air-connections, and in transporting and accurately placing the 35 converter.

In Letters Patent No. 104,592, granted to me the 21st day of June, 1870, I described a mode of applying to Bessemer converters linings previously prepared in sections within metallic shells, so that each section of lining, with 40 its containing shell, might be shipped within the main shell or body of the converter and there held by set-screws.

My present invention differs radically from 45 the above, in that it provides a way by which a complete converter-shell may be removed from its trunnions for repairs and immediately replaced by a new one without disturbing the trunnions in their bearings.

50 My improvement consists in constructing the trunnions, and a frame or ring connecting

them, independently of the shell of the converter, so that the shell can be readily taken out of the trunnion-ring and removed for repairs, and a repaired shell can be quickly substituted. This substitution may thus be made by means of a simple lift and car instead of a costly overhead-crane. In changing the shell instead of the whole converter the delay and labor of removing and repairing the trunnions, 55 pillow-block caps, and the air-connections are avoided.

I make the trunnion-ring of the converter either of forged or cast iron or steel. I prefer to cast the ring, the trunnions, and a part of 60 the air-pipe in one solid piece, and to strengthen this by a wrought-iron lining. I make the shell smaller in maximum exterior diameter than the interior of the trunnion-ring, so that the former will readily slip into the latter. I prefer to leave a space of about an inch between 65 the ring and the shell, to allow for the distortion of the latter by heat. I temporarily secure the shell to the ring for service by means of brackets and cotter-bolts that can be readily disconnected, or in any convenient or suitable manner. I prefer to remove the shell with its 70 nose down, so that the nose part can be readily repaired. The bottom may be removed with the shell; but I prefer to remove the bottom 75 by one of the usual methods before removing the shell. The shell may be hoisted out of the trunnion-ring or pulled out laterally; but I prefer to lower it upon a car. I therefore place the trunnion-ring at such a height above the 80 floor upon which the shell is to be repaired that the shell can be lowered out of the ring and removed laterally on a car. A hydraulic lift under the converter may either lower the shell upon the car or it may raise the car up to the 85 shell and lower both together. The car may then be drawn to the place where the lining of the shell is to be repaired, and here the shell may, if desired, be lifted into a mounted trunnion-ring, by which it may be rotated to facilitate 90 repairs.

One form of my invention is shown by the drawings forming a part of this specification.

The bottom J of the converter D, Figure 4, is removable in the usual manner. When the 95 bottom is removed, the shell may be lowered so as to pass out under the beam A B C on the

car L, as shown by the dotted lines K K. The converter is preferably hung under the beam, so as not to place its center inconveniently high above the general floor E.

5 Fig. 5 shows the trunnion-ring F and the shell at the dotted line H H. The shell is shown dropped out of the trunnion-ring upon the car L L by the lines G G.

Fig. 3 is a plan of the car L. To remove a shell I prefer to run the car L upon the table M of a hydraulic lift, and to raise it by the lift to the position shown by the dotted lines L' L', where it comes in contact with suitable lugs N N on the shell. The cotters are then knocked out of the bolts P P, Fig. 4, releasing the shell from the trunnion-ring, when the car, bearing the shell, may be lowered and run out to the place where the lining is to be repaired.

Figs. 1 and 2 show, respectively, a vertical and cross section of the trunnion-ring and part of the shell. The shell Q, by means of the brackets U, bears upon the trunnion-ring when the mouth of the shell is up. When the mouth is down the shell is held in the trunnion-ring by the cotter-bolts P. (See also P P, Fig. 4.) The trunnion-ring is a cast-iron hoop, S, and a wrought-iron lining, R. Wedges V may be used to keep the shell from moving laterally in the ring.

Fig. 6 is a plan of an ordinary Bessemer 30 plant, showing the converters W W and the ingot-pit.

A shell removed for repairs may be run out upon the turn-table Y, and thence to the position A a, after which a repaired shell, standing 35 at Z, may be run in and attached to the trunnion-ring.

Trunnion-rings may also be mounted at Z Z, by means of which the shells coming out for repairs may be turned either end or side up, 40 as desired.

What I claim, and desire to secure by Letters Patent, is—

1. A Bessemer converter having its main body or shell detachably connected to and 45 readily separable from the trunnions, so that the said shell may be removed for repair or relining without disturbing the trunnions, substantially as described.

2. The combination of trunnion-band F, converter-shell D, supporting-ring, flange or brackets U, and cotter-bolts P, substantially as and 50 for the purposes set forth.

A. L. HOLLEY.
